(57) **CLAIM**

The ornamental design for a bottle carrier for transport as shown and described.

DESCRIPTION

FIG. 1 is a perspective view of a bottle carrier for transport. FIG. 2 is a front view of the bottle carrier for transport shown in FIG. 1.

FIG. 3 is a back view of the bottle carrier for transport shown in FIG. 1.

FIG. 4 is a right view of the bottle carrier for transport shown in FIG. 1.

FIG. 5 is a left view of the bottle carrier for transport shown in FIG. 1.

FIG. 6 is a top view of the bottle carrier for transport shown in FIG. 1.

FIG. 7 is a bottom view of the bottle carrier for transport shown in FIG. 1.

FIG. 8 is a perspective view of another bottle carrier for transport.

FIG. 9 is a front view of the bottle carrier for transport shown in FIG. 8.

FIG. 10 is a back view of the bottle carrier for transport shown in FIG. 8.

FIG. 11 is a right view of the bottle carrier for transport shown in FIG. 8.

FIG. 12 is a left view of the bottle carrier for transport shown in FIG. 8.

FIG. 13 is a top view of the bottle carrier for transport shown in FIG. 8; and,

(Continued)

FIG. 14 is a bottom view of the bottle carrier for transport shown in FIG. 8.

The broken lines represent fold lines that do not form part of the claimed design.

1 Claim, 14 Drawing Sheets
